CLAIM

The ornamental design for a small objects organizer for an attache case or the like, as shown and described.

DESCRIPTION

FIG. 1 is a perspective view of a small objects organizer for an attache case or the like showing my new design.

FIG. 2 is a left end elevational view.

FIG. 3 is a right end elevational view.

FIG. 4 is a top plan view.

FIG. 5 is a rear elevational view.

FIG. 6 is a bottom plan view.

FIG. 7 is a perspective view similar to FIG. 1 with the compartments open.

FIG. 3.

FIG. 2.

FIG. 4.

FIG. 5.

FIG. 6.

FIG. 7.
